UNITED STATES PATENT OFFICE.

RICHARD DRAKE, OF RACINE, WISCONSIN, ASSIGNOR TO THE AMERICAN MANUFACTURERS SALES COMPANY, A CORPORATION OF WISCONSIN.

TOBACCO-CAN.

1,305,256.

Specification of Letters Patent. Patented June 3, 1919.

Application filed May 22, 1915. Serial No. 29,884.

To all whom it may concern:

Be it known that I, RICHARD DRAKE, a citizen of the United States, residing at Racine, in the county of Racine and State of 5 Wisconsin, have invented new and useful Improvements in Tobacco-Cans, of which the following is a specification.

This invention relates to a tobacco can and it consists in the novel features herein- 10 after described and claimed.

An object of the invention is to provide in a relatively long and flat tobacco can, means for supporting the package of tobacco which is contained within the can, at a point spaced 15 from the bottom thereof, in order that the fingers may be inserted in the can and reach the tobacco for the purpose of breaking the same up in the package in order that it may be readily poured from the can into a pipe 20 or cigarette paper.

With the above object in view the invention consists in providing at the side of the can a curved incision which leaves a tongue at the inner side of the incision. This tongue 25 normally lies in the same plane as that occupied by the side of the can at which it is formed, and when the package of tobacco is inserted in the can, the tongue lies against the side of the package and co-operates with 30 the side of the can in protecting the package and its contents. When the tobacco in the package is partially removed therefrom, or consumed, the package is moved, whereby its bottom is brought toward the upper edge 35 of the can and the said tongue is then pressed in an inward direction under the lower end of the package and the package may rest upon the tongue and it is thereby supported in a spaced position above the bottom of the can. When the package is so supported, the fingers and thumb may be readily inserted in the same for the purpose 40 of breaking up the tobacco at or near the bottom of the package in order that the said 45 tobacco may be poured as above indicated.

In the accompanying drawing:—

Figure 1 is a side elevation of the can.

Fig. 2 is a section on line 2—2 of Fig. 1.

Fig. 3 is a similar section showing the contents in elevated position.

Fig. 4 is a section taken on the line 3—3 of Fig. 3.

The can 1 is of the usual form or pattern, the said can being comparatively long and 55 flat in order that it may fit snugly in the

pocket of a garment. The package 2 of tobacco is housed in the can 1 in the usual manner. The can 1 is provided at one side with a curved incision 3 which forms a tongue 4 at the side of the can. When the package 2 is inserted in the can the tongue 4 lies in the same plane as that occupied by the side of the can to which the tongue is attached. As the tobacco from the package 2 is consumed or removed, it becomes difficult to reach the 60 same with the fingers in order to break the tobacco for the purpose of pouring it out of the can. In this instance, the package 2 is raised in the can so that the lower end of the package is spaced from the bottom of 65 the can and the tongue 4 is bent in an inward direction under the lower end of the package and serves as a support for the same. When the package is in this position the thumb and fingers may be readily inserted in the can for breaking the tobacco 70 preparatory to pouring.

Therefore it will be seen that simple and cheap means is provided in combination with a can structure for supporting a tobacco package in spaced position with relation to the bottom of the can, and the supporting tongue may be easily and quickly disposed below the lower end of the package 75 and support the same in the said spaced position from the bottom.

Having described the invention what is claimed is:—

1. The combination of an outer container, an inner package slideable in said container, and a member normally permitting free outward sliding movement of said package in said container, and bendable only after a predetermined definite outward sliding movement of said package to become effective to arrest a return movement of said package back to its original position in said container.

2. An outer container, having a substantially uniform cross section, the contents of said container being bodily capable of longitudinal sliding movement within said container, said container being provided with a member normally lying substantially in the plane of the side of said container and movable inwardly into self-retaining position to form a stop to limit the sliding movement of the contents within said container.

3. The combination of a protective outer container having substantially parallel sides,

whereby its cross section is substantially uniform throughout its length, and an inner package longitudinally slidable within said container, said container being provided, intermediate its ends, with a member normally lying substantially in the plane of one of the sides of said container and readily bendable inwardly beyond its elastic limit to form an automatically acting stop to arrest longitudinal movement of said package within said container.

4. The combination of a protective outer container having substantially parallel sides, whereby its cross section is substantially uniform throughout its length, and an inner package longitudinally slidable within said container, said container being provided, intermediate its ends, with a member normally lying substantially in the plane of one of the sides of said container and readily bendable inwardly into a self-retaining position to normally form a stop to arrest longitudinal movement of said package within said container, said member being accessible for bending purposes from the exterior of the package.

5. In a can adapted to contain tobacco in package form, means for holding the package in a predetermined position comprising a seat for said package formed by an incision in the side of the can, said seat being formed

by bending inwardly the cut portion so that it will retain a position at right angles to the side of the can whereby the contents may rest thereon to permit the easy removal of 35 such contents from the can.

6. A tobacco can having a uniform cross-section throughout its length and arranged to permit a free outward endwise sliding movement of a paper package containing tobacco in comminuted condition, the side of the can intermediate its length being incised to form a tongue capable of being readily bent inwardly beyond its elastic limit to form a transverse self-retaining shelf for 40 supporting the package in a position with its lower end spaced apart from the bottom of the can.

7. A can provided at its side with an incision forming a tongue of the material constituting the side of the can said tongue being readily bendable beyond its elastic limit in an inward direction into self retaining position to automatically support an article in a position spaced from the bottom of the 55 can.

In testimony whereof I affix my signature in presence of two witnesses.

RICHARD DRAKE.
